DRAPERY SLIDE FOR A CURTAIN ROD

Samuel Galietti, 1360 NE. 204th Terrace,
North Miami Beach, Fla. 33162

Filed Aug. 6, 1975, Ser. No. 602,475

Term of patent 14 years

Int. Cl. D8—08

U.S. Cl. D8—248

FIG. 1

FIG. 2

FIG. 3

FIG. 4

FIG. 5

FIG. 1 is a top plan view of a drapery slide for a curtain rod showing my new design;

FIG. 2 is a front elevational view thereof;

FIG. 3 is an elevational view of the left side thereof, the right side being identical in reverse;

FIG. 4 is a rear elevational view thereof; and

FIG. 5 is a bottom plan view thereof.

I claim:

The ornamental design for a drapery slide for a curtain rod, as shown and described.
